FORM FOR USE IN SHUTTERING

Herbert Charles Huish, London, England

Application July 19, 1947, Serial No. 762,064
In Great Britain March 21, 1946

Section 1, Public Law 690, August 8, 1946
Patent expires March 21, 1966

4 Claims. (Cl. 25—131)

1

The present invention relates to improvements in, and relating to, forms for use in shuttering as employed for constructional work in concrete, the primary object of the invention being to provide a flexible form suitable for use in the erection of shuttering having curved contours. The improved form forming the subject of the invention is such that its curvature may be varied according to the required contour of the shuttering but it is also well adapted for use in the production of flat surfaces.

The improved form according to the invention comprises a four-sided flexible metal sheet or face plate having a number of stiffening members such as channel or angle irons, extending between two opposite edges of the sheet at the back thereof, and welded or otherwise affixed to the sheet in spaced and, usually, parallel relationship with one another, one or a number of flexible bars or bars of preformed, curved, contour disposed transversely of and connected with said stiffening members in such manner as to be capable of being moved in the transverse direction relative to at least some of said stiffening members and sheets of corrugated steel or like material, flexible in one direction, disposed between the metal sheet and the flexible or pre-curved bars with the lines of the corrugations extending in the general direction parallel to the said stiffening members.

Two of the stiffening members may be formed of channel irons, welded or otherwise fixed near two edges of the plate, the plate at one of these edges extending a short distance outwards beyond the channel iron and at the other edge being set back a corresponding distance relative to the other channel iron. One of these channel irons is disposed with the channel inwardly directed and the other with the channel outwardly directed and the first mentioned is provided on its outer surface with projecting parts adapted to nest within the channel of a channel iron similar to the second mentioned on another form when two of the forms are brought into edge to edge relationship, the adjacent edges of the face plates or sheets abutting one another to form a continuous smooth surface at the junction.

At the inner sides of the edge-mounted channel irons are welded metal plates and angle irons to which the ends of the flexible or preformed curved bars may be clamped to retain the desired curvature of the face plate of the form. For this purpose the ends of the flexible bars may be slotted or forked to engage bolts carried by the angle irons, and in one arrangement the surface of the slotted ends of the bars is toothed or serrated for engagement with correspondingly serrated washers beneath the heads of the bolts.

The projecting parts, referred to above as be-

2

ing provided on the edge channel iron, with the inwardly projecting channel, may be formed by lugs of a height corresponding to the width of overlap of the edge of the metal sheet of one or other of the channel irons, and of a maximum width corresponding to the internal width of a channel, such lugs being welded or otherwise fixed to the outer surface of the bottom of the channel iron and spaced from the sheet or face plate by a distance corresponding to the thickness of a channel iron wall.

In the preferred arrangement however the walls of the channel iron, having the projections are deformed in such manner as to produce a channel bottom of smaller width than the main part of the channel, the external width of such channel bottom being equal to the internal width of the main part, the channel bottom so formed constituting the projections.

The adjoining and nested channel irons of adjacent forms are connected together by any convenient means, e. g., by bolting or, by the use of clamping means, such as those described in my co-pending patent application Ser. No. 762,063.

The invention is illustrated by way of example in the accompanying drawings in which:

Figure 1 is a view in rear elevation of a complete form.

Figure 2 is a view from above of the upper edge of the form shown in Figure 1, the form being shown curved.

Figures 3, 4, 5 and 6 are views in section and on a larger scale and taken on the lines 3—3, 4—4, 5—5 and 6—6 respectively of Figure 1.

Figure 7 is a view in elevation and also on a larger scale of parts shown in Figure 3, and Figure 8 shows a detail.

Referring to the drawings, 1 represents a flexible rectangular face-plate formed of sheet steel, to parallel edges of which are welded edge stiffening members 2 and 3 formed of channel iron.

The stiffening member 2 at one edge is a plain, channel iron of rectangular section (Figure 6), and is mounted with the channel outwardly directed as shown, and with the edges 4 projecting outwards beyond the edge 5 of the sheet 1. The stiffening member 3 at the other edge is a channel iron, the side walls of which are deformed as shown at 6 so as to produce a channel bottom 7 of an external width which is equal to the internal width of the channel of member 2. The outer extremity of projection 7 formed by the narrow bottom of channel member 3 is disposed in register with the edge of the sheet 1, and a space is provided between the edge of the sheet and the projection, for the entry of one wall of a channel iron 2 of a second form.

One or more additional stiffening members 8 may be affixed to the sheet 1 in spaced relationship between and parallel to the members 2 and

3, such additional members being formed conveniently of angle iron as shown in Figures 4 and 5, welded to the face-plate 1.

To the external surface of the bottom of the channel or channel iron 2 is welded an angle iron 9 with the free flange thereof away from the face-plate 1, and to the inner surface of the wall of angle iron 3 away from the face-plate 1 is welded a flat strip or bar 10, one edge of which extends from within the channel of said channel iron 3.

Two or more metal bars 11, three in the example shown, are disposed transversely of and connected to the angle iron 9 of channel iron 2 and the bar 10 of the channel iron 3, by means of bolts or screws 12. The bars 11 may be of metal strip capable of being flexed to the desired curvature, the strip being provided with slots 13 for the passage of the bolts or screws 12 to permit adjustment of the bars 11 transversely of the angle irons 2 and 3 and of the additional stiffening members 8 as the face-plate 1 is bent to the desired curvature prior to clamping of the bars 11. Alternatively the bars 11 may be stiff bars of preformed curvature. When in the connected position the bars 11 are spaced from the rear surface of the face-plate 1 and in the space are accommodated corrugated steel sheets 14 disposed with the lines of the corrugation generally parallel to the channel irons 2 and 3.

In the case illustrated the bars 11 are connected with a stiffener 8 located in the region of the centre line of the form in such a manner as to be incapable of transverse movement relative thereto; the bolt and slot connection 12 and 13 described above being provided at the edge stiffeners 2 and 3 and the remaining stiffeners 8 between the centre line and the edges.

The corrugated steel sheets 14 may be retained in position by disposing them with a groove or corrugation enveloping one of the angle iron stiffeners 8 (see Figure 5) the bolts 12 securing the slotted bars 11 to that angle iron passing through holes in the corrugated sheet. In such case the small lugs 15 of relatively small width are provided on the angle iron 8 for engagement by the bolts 12.

Other stiffening angle irons 8 such as that of Figure 4 may be left free of the corrugated sheets 14 or in other words the edges of separate corrugated sheets may lie at each side of the angle iron.

The ends of the bars 11 instead of being slotted may be forked as shown in Figure 8 and the surface of the bar ends, whether forked or slotted, may be provided with serrations 16 for engagement by a correspondingly serrated washer 17 provided beneath the head of the bolt.

In the case of narrow forms the intermediate stiffening angle irons 8 may be omitted.

The sheets of corrugated steel 14 between the metal face-plate 1 and the bars 11 readily accommodate themselves to the required curvature of the face-plate and thereafter constitute very efficient bracing elements. The corrugated steel sheets are preferably somewhat shorter than the height of the metal face-plate 1.

The improved form may of course also be used flat, i. e. with straight or unflexed bars 11.

A number of the forms as described above may be readily assembled edge to edge by nesting the projections 7 of one in the channel of channel iron 2 of the next and so on, and they may be

used to produce either concave or convex surfaces and surfaces of simple or compound curvature. They are also well adapted for use in conjunction with the flat forms described in my co-pending application for patent Ser. No. 762,063 when it is desired to produce curved surfaces merging into flat surfaces.

I claim:

1. A form for shuttering as used for constructional work in concrete, comprising a four-sided flexible metal face-plate, a number of stiffening members extending between two opposite edges of the sheet at the back thereof and fixed to the face-plate in spaced and general parallel relationship with one another, and including one stiffening member of channel section mounted in the region of one edge of the face-plate with the channel outwardly directed, a second stiffening member mounted in the region of the opposite edge of the face-plate and projections on said second member extending in the outward direction from said second member and of a size to nest within channel section members similar to the said first stiffening member of channel section of a similar form, at least one flexible bar disposed transversely of and connected with said stiffening members in such manner as to permit relative adjusting movement in the transverse direction between said bar and at least one of said first and second members and at least one sheet of corrugated material flexible in one direction disposed between the back of the face-plate and the said flexible bar with the lines of the corrugations extending in the general direction parallel to the said stiffening members.

2. A form as claimed in claim 1, wherein one of the first and second stiffening members is mounted so as to project outwards by a short distance from the edge of the face-plate at which it is mounted and the other is set back by a similar short distance from the edge of the face-plate at which it is mounted.

3. A form as claimed in claim 1 and including at least one stiffening member fixed to the back of the face-plate intermediate the said first and second stiffening members, the said flexible bar being affixed to one of said intermediate stiffening members in such a manner as to be incapable of transverse movement relative thereto.

4. A form as claimed in claim 1 wherein the said second stiffening member is also of channel section with the walls of the channel deformed to provide the outwardly extending projection in the form of a channel bottom of smaller width than that of the main portion of the channel, the external width of said channel bottom being equal to the internal width of the said first channel section stiffening member.
